UNITED STATES PATENT OFFICE.

ROBERT ABELL, OF UTTOXETER, BOROUGH OF DERBY, ENGLAND.

PICKING-MOTION FOR VERTICAL LOOMS.

957,725.

Specification of Letters Patent.

Patented May 10, 1910.

Application filed November 6, 1908. Serial No. 461,422.

To all whom it may concern:

Be it known that I, ROBERT ABELL, a subject of the King of Great Britain and Ireland, residing at Elm Tree House, Uttoxeter, New Road, in the county borough of Derby, England, have invented new and useful Improvements in the Picking-Motion of Vertical Looms, of which the following is a specification.

10 The object of my invention is to effect certain improvements in the picking motion of a loom or textile machine in which the warp threads are situated in a vertical plane, the harness frames or heddles are horizontal, 15 and which is designed to weave a number of similar fabrics in parallel vertical planes.

Referring to the drawings which form a part of this specification:—Figure 1 is an end elevation of a loom constructed and arranged according to my invention, illustrating only such parts thereof as are necessary, 20 for the explanation of the said invention. Fig. 2 is an enlarged vertical section on line *a—a* of Fig. 1. Fig. 3 is a longitudinal section on line *b—b* of Fig. 2.

In carrying out my invention I provide or form each shuttle *c* with a rack *d* on the underside thereof to engage a pinion *e* keyed on a shaft *f* running the whole length of the 30 machine; there are two of these shafts *f*, *f'*, one on each side of the reed frame *g*, the positions of said shafts *f*, *f'* being so arranged that the racks *d* on the underside of the shuttles *c* are in engagement with the pinions *e* 35 on the shaft on one side of the reed space before they leave the pinions on the shaft on the other side; the shuttles slide upon guides or the like *s*.

Both of the shafts *f*, *f'*, preferably pass 40 through one end frame *h* of the machine and on each of them at this outer end is further keyed another pinion *j*. Both of these pinions engage a quadrant *k* also mounted on

the end frame *h* of the machine. This quadrant is coupled up by means of a connecting 45 rod *l* to a short crank *m*, the latter being keyed on to a toothed wheel *n*, having two short blanks or dwells *o* of concave form on opposite sides thereof. This wheel gears with another wheel *p* fast on the driving 50 shaft *q* of the machine and has two longer blanks or dwells *r* thereon.

The dwells on the two toothed wheels last mentioned (*n* and *p* respectively) are so arranged and timed that while they are in engagement they give the necessary dwell or rest to the shuttles on either side to allow for the rise and fall of the reed: the toothed portions of said wheels projecting beyond the face of the dwells or rests thereon engage as the driving shaft revolves and in combination with the quadrant *k*, pinions *j*, shafts *f*, *f'*, pinions *e* and racks *d* give the requisite throw to the shuttles.

Having now described my invention, 65 what I claim as new and desire to secure by Letters Patent is:—

In a vertical loom, the combination of reciprocating upright shuttles, placed side by side, racks on the bottom of the shuttles, 70 pinions engaging with said racks, horizontal shafts carrying said pinions, pinions on the ends of said shafts, a toothed quadrant engaging with the last named pinions, a pinion having dwells thereon, means for connecting said pinion with the quadrant, and a gear wheel having dwells thereon engaging with the last named pinion said gear wheel being connected with the driving means.

In testimony whereof I have signed my 80 name to this specification in the presence of two subscribing witnesses.

ROBERT ABELL.
